US00D894301S

(12) **United States Design Patent** (10) Patent No.: **US D894,301 S**
 Parsons et al. (45) Date of Patent: **** Aug. 25, 2020**

(54) **GOLF CLUB HEAD**(71) Applicant: **PARSONS XTREME GOLF, LLC**,
Scottsdale, AZ (US)(72) Inventors: **Robert R. Parsons**, Scottsdale, AZ
(US); **Michael R. Nicolette**, Scottsdale,
AZ (US); **Bradley D. Schweigert**,
Anthem, AZ (US)(73) Assignee: **PARSONS XTREME GOLF, LLC**,
Scottsdale, AZ (US)(***) Term: **15 Years**(21) Appl. No.: **29/679,577**(22) Filed: **Feb. 7, 2019****Related U.S. Application Data**(63) Continuation-in-part of application No. 29/672,106,
filed on Dec. 3, 2019, now abandoned, and a
continuation-in-part of application No. 29/671,984,
filed on Nov. 30, 2018, now abandoned.(51) **LOC (12) Cl.** ..... **21-02**(52) **U.S. Cl.**USPC ..... **D21/747**(58) **Field of Classification Search**USPC D21/747-751, 759
